UNITED STATES PATENT OFFICE.

FREDERICK W. HAGEMEYER, OF NEW YORK, N. Y.

WINDOW-SHADE SUPPORT.

1,079,940.

Specification of Letters Patent.

Patented Dec. 2, 1913.

Application filed May 7, 1913. Serial No. 765,984.

To all whom it may concern:

Be it known that I, FREDERICK W. HAGEMEYER, a citizen of the United States of America, residing at New York city, borough of Brooklyn, county of Kings, State of New York, have invented certain new and useful Improvements in Window-Shade Supports, of which the following is a full, clear, and exact description.

This invention relates to an improvement in window-shade brackets or supports, the object being to provide a means adapted to support a shade roller which can be adjusted in order to change the position of the shade carried thereby, relative to the top and bottom of the window-frame. In other words, my improved shade support is constructed to permit the shade to be located in a plurality of positions intermediate the top and bottom of the window-frame, the advantage being that a window may be lowered from the top, and the position of the shade changed, so as to permit of the free passage of air and at the same time preventing the annoying flapping of the shade.

As now commonly supported or hung window shades will on windy days flap when the window is lowered from the top unless the shade is rolled up, which permits the sunlight to enter. With my improved device the window may be lowered and the position of the shade changed so as to, as stated above, allow for the free passage of air and permit that part of the window, below the opening, to be covered by the shade.

I will now proceed to describe my invention in detail, the novel features of which I will point out in the appended claims, reference being had to the accompanying drawings, forming part hereof, wherein:

Figure 1 is a face view of a window looking from the inside of a room, the upper pane being lowered and showing my shade-support; Fig. 2 is an enlarged vertical section, the section being taken on a line 2—2 in Fig. 1, the shade being omitted; Fig. 3 is an enlarged detail view, partly in section, of one side of the adjustable frame.

Referring to the drawings, a window frame is indicated by the numeral 1, the said frame being provided with the usual slideable window sashes 2 and 3 carrying the panes 4 and 5. As herein embodied my im-

proved device comprises an adjustable frame 55 consisting of the vertically disposed rods 6 and 7 which, at their lower ends, are connected by a rail 8, the said rail passing through a slot 9 in each vertically disposed supporting element 10 and 11. The supporting elements or plates 10 and 11 are, at their ends, secured to the window frame 1, in this instance, by brackets 12 and 13. The manner of securing the elements 10 and 11 will have to vary according to the style of 60 window-frame in use. In some instances the elements 10 and 11 would have to be secured to the plaster, or concrete, surrounding the window-frame.

The shade, which is herein indicated, by 70 14 is carried by the rods 6 and 7 preferably at the upper end thereof, and in this instance I have employed blocks 15 and 16 which are secured to the upper end of the rods 6 and 7. (See Fig. 3.) Each block 75 15 and 16 is provided with a slot 17 through which the plates 10 and 11 freely pass. The block 15 is provided with a rectangular slot 18 (see Fig. 2), which receives the flattened end pin 19 of the shade-roller. The block 80 16 carries a round opening 20 (not shown in detail) to receive the round end pin 21 of the shade. (See Fig. 1.)

To adapt the shade-frame to be moved to, and retained in, different positions, I 85 provide retaining means which will hold the frame in the adjusted positions. In this instance, the retaining means consists of a plurality of recesses 22 (Fig. 2) in each plate 10 and 11. The recesses 22 communicate with the slots 9 in the plates 10 and 11 and are adapted to receive the rail 8.

To change the position of the shade 14 the rail 8 will be moved out of the recess in which it may be and moved to a higher or 95 lower position, at which points other recesses will be located. The blocks 15 and 16 will swing enough to allow for the manipulation of the said frame.

As shown in Fig. 1 the shade 14 is located 100 below the opening caused by lowering the sash 2; hence air can flow through said opening without coming in contact with the shade 14, at the same time the lower portion of the window can be covered by the shade. 105 In this instance the lower pane is only partly covered. The shade-roller can, however, be adjusted to a position at the top of

the window. In the event of the upper pane being closed this might be desirable.

Having now described my invention, what I claim and desire to secure by Letters Patent is:

1. A supporting device for shades consisting of slotted plates, and a plurality of recesses in communication therewith, blocks slidably mounted on said plates adapted to support a shade, rods carried by said blocks and a rail carried by said blocks passing through said slots and adapted to engage said recesses.

2. In combination, a pair of plates having longitudinally spaced recesses, shade supporting blocks slidable on the plates, members depending from the blocks, and rods connecting the lower ends of the members

and movable in the recesses to support the blocks in different elevations.

3. In combination, a pair of plates having longitudinal slots and recesses in communication therewith, blocks slidable on the plates and adapted to support a window shade, members depending from the blocks and movable adjacent the plates, and a rod connected to the lower ends of the members and adapted to move into the slots and move into and out of the recesses to support the blocks in different elevations.

Signed at New York city, N. Y., this 6th day of May, 1913.

FREDERICK W. HAGEMEYER.
